DESIGN FOR A COMBINATION STREET DRESS AND EVENING DRESS

Doris Mandelker, Great Neck, N. Y.

Application April 23, 1941, Serial No. 100,575

Term of patent 3½ years

To all whom it may concern:

Be it known that I, Doris Mandelker, a citizen of the United States, residing in Great Neck, Long Island, in the county of Nassau and State of New York, have invented a new, original, and ornamental Design for a Combination Street Dress and Evening Dress, of which the following is a specification, reference being had to the accompanying drawings, forming part thereof, in which—

Figure 1 is a front view of a combination street dress and evening dress, showing my new design;

Figure 2 is a rear view of Figure 1;

Figure 3 is a front view of the street dress thereof; and

Figure 4 is a rear view of Figure 3.

I claim:

The ornamental design for a combination street dress and evening dress, as shown.

DORIS MANDELKER.
